(57) **CLAIM**

The ornamental design for a swimwear, as shown and described.

DESCRIPTION

FIG. 1 is a front perspective view of the swimwear, as shown in a stretched configuration;

FIG. 2 is a back perspective view thereof;

FIG. 3 is a front elevation view of the swimwear, as shown in a flat configuration;

FIG. 4 is a back elevation view thereof;

FIG. 5 is a back elevation of the swimwear, showing the interior as shown in a flat configuration;

FIG. 6 is a front elevation view thereof; and,

FIG. 7 is an inverted front elevation view of the swimwear, showing the interior, and shown in an alternative configuration with the portions of the swimwear rolled-up.

The broken lines depict claimed stitching of the swimwear.

1 Claim, 7 Drawing Sheets
